UNITED STATES PATENT OFFICE.

LOUIS V. ARONSON, OF NEWARK, NEW JERSEY.

BLOTTER.

1,411,557.

Specification of Letters Patent.

Patented Apr. 4, 1922.

Application filed February 12, 1921. Serial No. 444,441.

To all whom it may concern:

Be it known that I, LOUIS V. ARONSON, a citizen of the United States, residing in Newark, in the county of Essex and State 5 of New Jersey, have invented certain new and useful Improvements in Blotters, of which the following is a specification.

The purpose of this invention is primarily to produce a blotter support of unusually attractive appearance, lightness and strength, on which the blotter sheets are held distended over a curved resilient plate.

Another object is to provide means whereby one or more sheets may be attached or 15 disengaged in a simple and expeditious manner.

A further purpose is to provide a blotter support having a reinforced contact surface and a relatively stiff handle element convenient of manipulation.

These and other like objects are attained by the novel design, construction and arrangement of parts hereinafter described and shown in the accompanying drawings, 25 forming an essential part of this specification, and in which:—

Figure 1 is a top plan view of a blotter made in accordance with the invention.

Figure 2 is a side elevational view of the 30 same.

Figure 3 is a central transverse sectional view taken on line 3—3 of Figure 2.

Stated generally, the device consists of two parts only, one being a curved backing 35 plate against which the blotter sheets rest, the ends of the plate, together with the sheets, being inserted within open, curved recesses in the corresponding portions of the handle.

In order to obtain proper stiffness to the 40 plate a ridge is formed lengthwise in it, and the handle is stiffened by inturned flanges along its lower marginal edges, rendering it, in connection with the peculiar 45 form in which it is produced, essentially rigid and providing an efficient grip.

Referring now more particularly to the drawings, the backing element, designated by the numeral 10, is made from a sheet of thin resilient metal, as steel, of uniform 50 width, arranged in the form of an elongated rectangle, its side and end edges being smoothed, the said end edges designed to act as slide elements.

A raised ridge or rib 11 is formed to extend along the upper convex side of the

plate, nearly from end to end and preferably at the center, but it will be understood that more than one rib may be used and disposed in any desired manner.

A truss or girder shaped handle of convenient form for manipulative operation, is formed from another plate having a curved upper element 15, bowed oppositely from the plate 10, has at the extremities 16 of its main curved portion raised, reentrantly curved recesses 17 open, as at 18, along their entire length on their under side and adapted to receive the ends or slide elements of the plate 10 together with one or more sheets 70 of blotting material 20, the same being entered laterally or by springing the plate 10 to a lesser radius and inserting into the openings 17 from the bottom, the blotter sheets being frictionally held in operative position 75 against the face of the plate 10.

The side elements 21 of the handle are bent downward from the top 15 to a level plane 22 and are concavely curved equally on both sides from points near the extremities 16 to the highest central part 23 of the handle, while their bottom edges are turned inward forming narrow flanges 24 which materially stiffen the handle structure rendering it rigid under the application of applied pressure.

These several parts are obviously cheaply constructed, presenting a light but strong blotter support which may be finished by plating or enamel as preferred.

While certain preferred embodiments of this device have been shown and described, it will be understood that changes in the form, arrangements, proportions, sizes and details thereof may be made without departing from the scope of the invention as defined in the appended claims.

Having thus described my invention, what I desire to secure by Letters Patent and claim, is:—

1. A blotter support comprising a resilient metallic plate uniformly curved from end to end, a reinforcing rib integral with the concave side of said plate, and a truss shaped handle engageable with the end elements of 105 said plate, said handle narrowing on both sides towards its central highest point.

2. A blotter support comprising a yielding outwardly bowed flat plate having slide elements at its ends, a metal handle having 110 its end shaped to enclose said slide elements their full width, the truss shaped handle

body being hollow presenting symmetrical side elements curved inwardly, and upwardly towards the center and inturned flanges formed with the level bottom edges 5 of said side elements.

3. A blotter comprising a resilient sheet metal plate curved outwardly into the arc of a circle, an integral rib extending centrally along the concave side of said plate, 10 a truss shaped handle having curved end edges engageable with the ends of said plate and with blotter sheets disposed therebe-

tween, the side walls of said handle having straight lower edges and being convexly curved towards the center, its top wall being 15 curved upwardly from the ends, and interior stiffening flanges formed with the bottom edges of said side walls.

This specification signed and witnessed this eleventh day of February, 1921.

LOUIS V. ARONSON.
